UNITED STATES PATENT OFFICE.

ANDREW C. NYGAARD, OF RAWLINS, WYOMING.

DESIGN FOR A CLIP.

SPECIFICATION forming part of Design No. 30,278, dated February 28, 1898.

Application filed January 4, 1898. Serial No. 701,165. Term of patent 3½ years.

To all whom it may concern:

Be it known that I, ANDREW C. NYGAARD, of Rawlins, in the county of Carbon and State of Wyoming, have invented and produced a new and original Design for a Clip, of which the following is a specification, reference being had to the accompanying drawings, forming a part thereof, in which

Figure 1 is a perspective view of a clip embodying the features of my design, and Fig. 2 is a perspective view looking toward the bottom of said clip.

The body of the clip is L-shaped in general contour, consisting of an upright member A

and a horizontal member B, openings a appearing at the bottom of the upright member and at the rear of the horizontal member. A semicircular offset C is formed upon the front face of the vertical member, and an opening D appears to extend through the said offset C.

I claim—

The design for a clip herein shown and described.

ANDREW C. NYGAARD.
